UNITED STATES PATENT OFFICE.

BURTON W. SEYMOUR, SR., OF JAMESTOWN, NEW YORK.

MEANS FOR TREATING OIL WELLS.

Application filed August 28, 1926. Serial No. 132,067.

This invention relates to an improvement in means for treating oil wells, and more particularly in means for creating live steam within the well for the purpose of dissolving paraffine or other deleterious material in the oil bearing portion of the well.

It has been found that after a certain length of time the output of an oil well falls off, due to the gradual blocking of the passages through which the oil flows by the gradual formation of paraffine or other thickened products of petroleum.

Attempts have been made to correct this condition by the introduction of casings into the well containing a limited amount of water and heated billets onto which the water may fall. Such casings, however, are open to the objection that they must be withdrawn from the well within a short time to refill the water reservoir and to reheat the billets.

The object of the present invention is to avoid these objections by omitting the casing and water reservoir, and by providing a rod having a plate which will substantially close the well, and one or more heated billets supported below said plate, to which water is fed by means of pipes leading from said plate, the water being supplied thereto by pouring it directly into the well, such a construction eliminating the necessity of withdrawing the device to replenish the water supply.

Another object of this invention is to provide an electrically heated device, by which the billet or billets and the water are kept hot, so that the creating of steam in the oil bearing chamber can continue without interruption until the paraffine and other material is fully dissolved, leaving the oil passages clear and free.

A further object of this invention is to provide pipes by which the water can be fed to various portions of the billet or billets, which pipes will either be parallel to the billet or billets having outlets at the ends, or be coiled around the billet or billets and have a plurality of openings along the sides.

Other objects of this invention reside in the details of construction as will appear from a consideration of the following specification taken in connection with the drawings which form a part thereof, and in

of one embodiment of this invention, shown in position in an oil well;

Fig. 2 is a sectional view of the upper end of the steamer taken along the line 2—2 of 60 Figure 1;

Fig. 3 is a cross section of the steamer taken along the line 3—3 of Figure 1;

Fig. 4 is a sectional view of one modification of the steamer; and

Fig. 5 is a side elevation of another modification of the steamer.

This invention is intended to be used in oil wells for creating steam in the oil bearing chamber 10 of a well and is introduced 70 therein through a drilled hole 11.

The device comprises a hollow rod or tube 12, which is adapted to support a billet 13 slipped over the rod, and fixed in place by a pin 14 passed through the bottom of the 75 rod 12 or any other suitable manner. Threaded upon or otherwise fixed on the rod 12 is a cupped plate or bowl 15, having a plurality of perforations 16 therein.

The perforations 16 may be left free 80 (Figure 1), or pipes 17 may be fastened to the underside of the plate 15, into which pipes the perforations 16 open. The pipes 17 extend adjacent the billet 13 and may be of various conformations. As shown in 85 Figure 4, the pipes may be parallel to the rod 12, and vary in length, having outlets 18 at the ends inclined toward the wall of the billet 13. Figure 5 shows the pipes 16 coiled around the billet, each pipe having 90 one or more outlets 19 directed toward the wall of the billet 13.

The plate 15 is preferably of a diameter slightly less than that of the hole 11 and the pipes 16 and billets 13 are similarly formed. 95 In the outer edge 20 of the plate 15 is formed an annular groove 21, in which are introduced one or more expansion rings 22. These rings substantially close the space between the plate 15 and the wall of the hole 100 11 for a purpose to be set forth below.

The device is raised or lowered by means of a cable which is engaged in a loop 23, here shown as integral with the plate 15, but obviously not necessarily so. As shown 105 in Figure 1, the device is lowered into the well until the billet 13 enters the oil bearing chamber 10 to be treated. The plate 15 remains in the hole 11, the rings 22 bearing against the inner wall, thus closing the well 110 above the chamber 10.

When the parts are so located, water is

Fig. 1 is a side elevation partly in section

poured directly into the well and falls onto the plate 15, from which it passes through the perforations 16, directly onto the billet 13, as in Figure 1, or into the pipes 17, as 5 in Figures 4 and 5, and thence through outlets 18 or 19, onto the heated billet 13. The 10 heat in the billet transforms the water into steam, which fills the chamber 10, and attacks the paraffine or other matter, blocking the oil passages, causing it to melt and free the passages.

Within the rod 12 may be placed a heating element 24, shown in Figure 1 as comprising a coil 25, surrounding a central post 26, 15 and energized by a lead wire 27. The wire 27 enters the rod 12 through a passage 28, the mouth of which is closed by a plug 29. This coil will keep the billet 13 hot, and thus 20 avoid the necessity of withdrawing the device for reheating.

In Figure 1 the top of the billet 13 is cupped at 30 so that the water falling onto it through the perforations 16 will travel down the space 31 between the rod 12 of 25 the billet 13. A plurality of outlets 32 permit the steam formed in the space 30 to escape.

When the structure shown in Figures 4 and 5 is employed, the outlets 32 may be 30 omitted as unnecessary, since the steam passes directly from the outer surface of the billet or billets 13 into the chamber 10. The heating element 24 may be omitted or not used, in which case, of course, it will be necessary 35 to reheat the billet 13 from time to time.

In place of the single billet 13 shown and described, it is obvious that a plurality of billets could be used, and while certain embodiments have been shown and described, I am not limited thereto, since it is obvious 40 that embodiments can be made without departing from the spirit and scope of this invention as set forth in the following 45 claims.

Having thus set forth my invention what I claim as new and for which I desire protection by Letters Patent is:

1. Means for treating an oil well comprising a rod, adapted to support a heated billet, 50 and a cupped plate on said rod above said billet, having perforations therethrough, said rod being hung in the well to be treated with the heated billet in the oil bearing portion, and said plate closing the well 55 above said portion, whereby water poured into said well will pass through said perforations onto said heated billet and be transformed into steam.

2. Means for treating an oil well comprising a rod, adapted to support a heated billet, a cupped plate on said rod above said billet having perforations therethrough, pipes leading from said plate adjacent said billet and having outlets therein, said rod being hung in the well to be treated with the heated billet in the oil bearing portion and said plate closing the well 60 above said portion, whereby water poured into said well will pass through said pipes and outlets 65 onto said heated billet, and be transformed into steam.

3. Means for treating an oil well comprising a hollow rod, adapted to support a billet, an electrically heated element carried 70 by said rod adjacent said billet for heating the same, a cupped plate on said rod above said billet having perforations therein, and pipes in communication with said perforations leading from said plate to points adjacent 75 said billet.

4. Means for treating an oil well, comprising a hollow rod adapted to support a billet, a cupped plate on said rod above said billet having perforations therethrough, and an electrically heated element carried by 80 said rod, said rod being hung in the well to be treated with the heated billet in the oil bearing portion and said plate closing the well 85 above said portion, whereby water poured into said well will pass through said perforations onto said billet and be transformed into steam.

In testimony whereof I have affixed my signature.

BURTON W. SEYMOUR, Sr.
